UNITED STATES PATENT OFFICE.

WILLIAM NICHOLLS, OF COLERAINE, MINNESOTA.

CAR-DOOR-OPERATING DEVICE.

1,169,278.

Specification of Letters Patent.

Patented Jan. 25, 1916.

Application filed February 23, 1915. Serial No. 9,907.

To all whom it may concern:

Be it known that I, WILLIAM NICHOLLS, a citizen of the United States, and resident of Coleraine, in the county of Itasca and 5 State of Minnesota, have invented certain new and useful Improvements in Car-Door-Operating Devices, of which the following is a specification.

My invention relates to a device for winding up the chains which operate the doors on drop-bottom railway cars. In such cars it is the practice to support the doors by chains wound upon shafts, the shafts being held by a pawl and ratchet. When the car is 15 unloaded the pawl is released and the weight of the load forces the drop-bottom doors open. To replace the doors it is necessary to wind up the chains. This winding-up operation is at present accomplished by the 20 use of a wrench or bar, which operation involves very considerable manual labor and in addition involves a serious element of risk to the men operating the bars or wrenches, for it has not infrequently happened that a bar or wrench has slipped from the hands of the operator and been thrown upward, causing serious accident. The purpose of my invention is to reduce the 25 manual labor and obviate the risk involved by winding up the chains, by means of a motor-driven mechanism so arranged as to be readily applicable to the car.

The invention would be more readily understood by reference to the accompanying 30 drawings, in which—

Figure 1 is a diagrammatic elevation of an ore car with the door opening device associated therewith, Fig. 2 is a transverse section through the door operating device, 40 and Fig. 3 is a side elevation of the same partly in section with a portion of the casting removed.

It is impossible in practice to stop cars exactly in the same place; furthermore, it is 45 desirable that one device shall serve a large number of cars; consequently it is necessary that to make the device thoroughly operative, it must be readily movable. In Fig. 1 I have shown it as suspended from an 50 overhead rail hung from the bottom chord of the roof trusses of a building, taking current for operating the motor in a manner similar to that used on overhead cranes. It is obvious, however, that in case there is 55 no overhead structure the device might be supported in some other manner. In the

drawings I have shown a motor 10 which may be of any approved type, either electric or pneumatic. This motor operates a shaft 11, upon which is keyed a worm 12. This 60 worm engages a worm wheel 13, which is mounted on a shaft 14. Likewise secured to the shaft 14 is a pinion 15 engaging a large gear 16 keyed to a shaft 17. A socket 19 is rigidly secured to the overhung end 65 18 of the shaft 17 in any suitable manner, this socket having a squared recess 20 for engagement with the car shaft, or I may mount a tooth clutch 21 on the overhung end of the shaft, as indicated in dotted lines 70 in Fig. 2, which clutch may engage a similar clutch on the door-operating shaft 27.

The operation is as follows: The drop-bottom doors of the car having been dumped in the usual manner, the device here described is swung into position so that the tooth clutch or squared socket engages with corresponding parts on the car, whereupon the motor is started and, because of the reduction in speed, the doors are closed slowly 80 and without manual labor or danger to the operator. In case of an electric motor, means will be provided for automatically cutting off the power in case the operator fails to cut it off manually after the 85 doors are closed, said means being shown in diagrammatic form in Fig. 3, in which 27 is an automatic cut-off, in series with the rheostat 29, and the field of motor 10. 30 represents a knife switch in the feed line to 90 the motor and control box 29. However, in the event of the failure of these devices to cut off the power, the motor and operating mechanism will revolve bodily. In such case I may provide a spring 22 in the suspending chain 23 in order to reduce the 95 shock. This chain engages suitable cables 24 carried by a trolley 25 running on tracks 26.

Obviously the construction shown is capable of much modification, particularly in the form and disposition of parts, and such modifications as are within the scope of my claims I consider within the spirit of my invention.

I claim:

1. The combination with a car having a door of a rotatable shaft for closing said door, a clutch on one end of the shaft, an overhead support and a trolley running on 110 said support, a motor flexibly suspended from the trolley, a second shaft, speed re-

- ducing mechanism between the motor and said second shaft, and a clutch on the end of said second shaft adapted to flexibly engage with the clutch on the end of said car shaft, substantially as described.
2. The combination with a car having a door of a rotatable shaft for closing said door, a clutch on one end of said shaft, a support and a trolley running on said support, a motor flexibly mounted on said support, a second shaft, speed reducing mecha-

nism between the motor and shaft, and a clutch on the end of said second shaft adapted to flexibly engage with the clutch on the end of the car shaft, substantially as described. 15

Signed at Coleraine, Minnesota, this 17th day of February, 1915.

WILLIAM NICHOLLS.
